HEAVY EQUIPMENT DOLLY

Earl Fox, Torrance, Calif., assignor of a fractional part
interest to August A. Pfaehler, Manhattan Beach, Los
Angeles, Calif.

Filed May 21, 1971, Ser. No. 145,998

Term of patent 14 years

Int. Cl. D12—05

U.S. Cl. D14—3 N

Fig. 4.

Fig. 5.

FIG. 1 is a perspective view of a heavy equipment dolly showing the new design;

FIG. 2 is a top view of the dolly shown in FIG. 1;

FIG. 3 is a bottom view of the dolly of FIG. 1;

FIG. 4 is an elevational view of the dolly illustrated in FIG. 1, looking along a line bisecting the two intersecting vertical side plates of the dolly; and

FIG. 5 is an elevational view of the dolly looking along a line perpendicular to one vertical side plate as shown in FIG. 4.

I claim:

The ornamental design for a heavy equipment dolly, substantially as shown.
